CLAIM

The ornamental design for an all terrain vehicle, as shown and described.

DESCRIPTION

FIG. 1 is a perspective view of an all terrain vehicle showing my new design;

FIG. 2 is a left side elevation view thereof;

FIG. 3 is a right side elevation view thereof;

FIG. 4 is a front elevation view thereof;

FIG. 5 is a rear elevation view thereof; and,

FIG. 6 is a top plan view thereof.

All structures indicated in broken lines are not part of the design sought to be patented.
